INVENTOR

UNITED STATES PATENT OFFICE.

WALTER M. STEPPACHER, OF PHILADELPHIA, PENNSYLVANIA.

TAB FOR NECKBANDS FOR SHIRTS.

1,122,327.

Specification of Letters Patent. Patented Dec. 29, 1914.

Application filed July 17, 1914. Serial No. 851,441.

To all whom it may concern:

Be it known that I, WALTER M. STEPPACHER, a citizen of the United States, residing in the city and county of Philadelphia, State of Pennsylvania, have invented 5 a new and useful Tab for Neckbands of Shirt, of which the following is a specification.

My invention consists of the provision on 10 the neck band of a shirt of a tab of the construction herein claimed whose object is to facilitate the opening of the pocket in said band ordinarily closed in starching or laundrying, whereby a stud may be inserted 15 conveniently in the hole in the outer fold containing the same.

The invention is satisfactorily illustrated 20 in the accompanying drawing, but the important instrumentalities thereof may be varied as long as they are within the scope 25 of the claims.

Figure 1 represents a rear elevation of a 30 neck band of a shirt embodying my invention. Fig. 2 represents a vertical section 35 thereof on an enlarged scale. Fig. 3 represents a similar vertical section thereof on an enlarged scale, but showing certain members in a different position from those in Fig. 2. Fig. 4 represents an elevation of a 40 portion of the neck band showing the primary formation of the tab above referred to. Fig. 5 represents a similar elevation showing 45 the successive steps of forming said tab.

Similar numerals of reference indicate 50 corresponding parts in the figures.

Referring to the drawings, 1 designates 55 the neck band of a shirt which excepting the feature of my invention applied thereto is of usual construction. Connected with the 60 outer fold of said band at the center of the back thereof is the tab 2 which depends therefrom and overhangs the adjacent portion of the shirt below said band where it is accessible so that it may be readily grasped 65 by the thumb and forefinger and drawn outwardly or rearwardly so that said fold may be separated from the inner fold, thus opening what is known as the pocket between the 70 two folds whereby a buttoning stud may be 75 inserted in the opening or hole 3 of the

band, access to which being rendered convenient by such opening of the pocket, it being well known that in the laundrying of the band, the folds thereof adhere due to the starching, and it is difficult to separate 55 the same as a thumb or finger cannot be introduced between them, and a knife or other implement if employed, is liable to cut the fabric, but here the tab 2 performs an important function in that it is free and within 60 reach, and may be subjected to an outward pull which then is imparted to the exterior fold of the band, thus destroying the holding power of the starch or breaking the connection of the two folds when said 65 exterior fold separates from the inner fold, and the hole 3 is uncovered from within for the application and insertion of the stud for the connection of the collar, as usual.

In the manufacture of the tab, I cut one 70 of the plies 4 of the band along the lines 5 forming the quadrilateral piece 6 which is turned down on the bend 7 below the band. Then said piece is folded inwardly on the diagonal cross lines 8, 8, converting the same 75 into the triangular shape which comprises the tab 2, the latter then being stitched to the adjacent plies of the band, the result being as in Fig. 1, said tab thus being formed of several thicknesses of the same material 80 as the ply 4, as shown in Figs. 2 and 3, and so possessing great strength, it being removed from the main portions of the band, thus avoiding increasing the thickness thereof especially about the buttonhole 3. 85

Having thus described my invention what I claim as new and desire to secure by Letters Patent, is:—

1. In a pocket for a neck band of a shirt, a ply of said band having an integral piece 90 thereof partly separated therefrom and turned down therefrom, and a tab formed of the lower portion of said piece folded on itself and depending from said band.

2. In a shirt, a neck band provided at 95 the back thereof with a tab adapted to facilitate the opening of the pocket within the inner and outer folds, the same being an integral member of one of the plies of said band turned out of the same and folded. 100

3. In a shirt, a neck band provided at the back thereof with a tab adapted to facilitate the opening of the pocket within the inner and outer folds, the same being composed of a quadrilateral piece of the material of one of the plies of said band folded

into triangular form, and secured to the adjacent portions of the band.

WALTER M. STEPPACHER.
